UNITED STATES PATENT OFFICE.

KENNETH DAVIS, OF ST. BENEDICT, PENNSYLVANIA, ASSIGNOR TO REMBRANDT
PEALE, OF ST. BENEDICT, PENNSYLVANIA.

SYSTEM AND APPARATUS FOR CONVEYING COAL.

Application filed December 12, 1918. Serial No. 266,505.

To all whom it may concern:

Be it known that I, KENNETH DAVIS, a citizen of the United States, residing at St. Benedict, in the State of Pennsylvania, have invented a new and useful System and Apparatus for Conveying Coal, of which the following is a specification.

The invention relates to mechanism and devices for handling and conveying coal from the face of mine rooms or breasts to a car or cars in or adjacent to the entry or heading, irrespective of the position or place of dislodgement of the coal at the breast or room face and adaptable to the gradual advancement of the breast or room face as the coal is dislodged from the vein.

Objects and advantages of the invention, will be set forth in part hereinafter and in part will be obvious herefrom, or may be learned by practice with the invention, the same being attained and realized through the steps and instrumentalities pointed out in the appended claims.

The invention consists in the novel steps, process, parts, arrangements, constructions, combinations and improvements herein shown and described.

The accompanying drawings, referred to herein and constituting a part hereof, illustrate certain steps in the process or system and the present preferred form of the apparatus or mechanism, and together with the description, serve to explain the principles of the invention.

Of the drawings:—

Fig. 1 is a diagrammatic plan of a room and heading with my system and apparatus operating therein;

Fig. 2 is a similar fragmentary diagram showing the car turned off the heading into the room neck;

Fig. 3 is a fragmentary, vertical section showing the external end of the fixed path conveyor, and the conveying of the coal into the car;

Fig. 4 is a fragmentary elevation, on an enlarged scale, of the conveyor drive and associated parts;

Fig. 5 is a fragmentary elevation of the inner end of the conveyor, showing the tension adjustment;

Fig. 6 is a top plan corresponding to Fig. 5;

Fig. 7 is a top plan of the "scraper" of the conveyor; and

Fig. 8 is a side view thereof.

The invention includes mechanism and devices for handling coal, one application thereof being where the coal is dislodged in relatively small quantities usually consecutively all along or across the room or breast face, by a miner or preferably by a machine, and is allowed to fall as it may upon the mine floor or bottom, in any location and quantity as found desirable or convenient. 60 A system of coal conveyance along a fixed-path or route from the general location of the breast or room face to a car or cars in, or just off, the entry or heading is provided. Intermediate between this conveying means 65 and the coal dislodging means, which latter operates as needs be at any point across and along the continuously receding room face, is provided an independently traveling coal conveying or transporting means, capable 70 of pursuing an independent and indeterminate path, that is, capable of traveling to and from any and all points in the room, or breast, and taking up the dislodged coal in substantial quantities from the point of 75 its dislodgement and depositing it in the path or operative reach of the fixed path conveying means.

Objects of the invention are to provide a means for efficiently and economically conveying coal from the room faces to the entry, especially in low veins, many of which are worked of a thickness of from two to three feet or even of less thickness; to effect 85 such conveyance of the coal while obviating the necessity of the workmen traveling to and fro in the low veins and avoiding the pushing of cars to and fro therein, and without necessitating the blasting of the top or bottom rock as is frequently done. The 90 cost of blasting the top or bottom rock in the rooms is well-nigh prohibitive as to cost, and the employment of men as car pushers who travel to and fro in the thin veins is 95 not only expensive but is so laborious and 100 uncomfortable that it is difficult to secure workmen for such work.

Further objects of the invention are to provide for effecting the objects previously stated without interfering with the timbering or propping of the top rock of the rooms, the props in many cases, as where the top rock is broken or rotten, being necessarily placed close together and very close also to the working face of the rooms. Through 105 110

the realization of the objects specified it is possible to work seams or veins which by reason of their thinness or of rotten or otherwise bad top rock are unworkable by the usual methods.

- Referring in detail to the embodiment illustrated by way of example in the accompanying drawings, the invention is shown applied to a seam or vein of coal of relatively small thickness, say about thirty inches and in said illustrated embodiment the method or system and the apparatus or mechanism is shown applied to the room and entry system of mining, the room being sometimes termed a breast and the entry being sometimes termed a heading or gangway. The invention is further exemplified in connection with a mine wherein the entry is blasted out at the bottom to give the requisite headroom. It will be understood that in its broader aspects the invention is applicable to coal veins of various thickness, to other kinds of minerals, and to other systems of mining.
- In such illustrated exemplification, the entry 1 is shown with the bottom portion thereof 2 blasted out below the level of the floor of the vein 3 of coal. The heading 1 is provided with a track 4 for the coal cars 5. A room 6 is shown opened off from the heading 1, the coal being dislodged or removed from the face 7, and the working face of the room thereby receding gradually from the heading a continually increasing distance, due to the mining or dislodgement of the coal.

The common practice in the past has been to run a track from the entry track into and along the entire length of the room, such track being extended as the face 7 of the room recedes, owing to the removal of the coal. Cars are run in from the heading and loaded with coal at the face of the room, and are then pushed back along the room track to the heading or entry. This method of handling coal is expensive, laborious and slow, as well as having other drawbacks and disadvantages. Other plans or systems have been employed, but they are open to serious objections for the reasons stated, as well as for other reasons. Where mining machines are employed, an endless conveyor is frequently attached to the mining machine and conveys the coal into the car standing on the room track before referred to. Such a conveyor is cumbersome and troublesome, requiring to be practically continuously moved as the mining machine progresses in its work, and the conveyor is in the way frequently of timbering, blasting, or other work.

All these disadvantages are avoided by my method or system and by the apparatus or mechanism herein described and large economies are also realized by my invention.

In the embodied exemplification, an endless conveyor traveling along a relatively fixed path is provided. In the embodied form, a sheave 15 is located at or near the mouth of the room, and a cooperating sheave 16 is located generally adjacent to the face 7 of the room. Over these sheaves travels an endless cable 17, to which are attached the coal conveying means or devices.

I have referred to this conveyor as having a relatively fixed path, although the inner sheave 16 is from time to time moved closer to the room face 7, as the face advances in the vein and recedes from the heading 1. This extension of the pathway of the conveyor can be made at convenience and after relatively considerable advances of the room face, and it is not necessary to keep this inner end of the conveyor in constant and close proximity either to the room face or to the mining machine as is the case with the usual conveyors. This is due to the fact that the intermediate and freely or independently traveling loader is employed between the room face and the conveyor just described. Thus I term the conveyor a relatively fixed path conveyor by reason of the advantages set forth.

Referring to the detailed structure of the present preferred exemplification, the outer sheave 15 is carried upon a stub shaft 18 mounted in a pedestal 19 carried on a base 20. The sheave 15 is preferably positioned at an angle or inclination from the horizontal, and is preferably employed as the driving sheave. The embodied form of driving means comprises a motor 21, mounted on the base 20, and having a pinion 22 upon the motor shaft meshing with the crown gear 23 on the sheave 15.

The inner sheave 16 as embodied, is movable to regulate the tension on cable 17, and for this purpose is journaled in a block 34, which block is slideable in a guideway in a horizontal arm 35, said arm terminating in a T head 36 bolted to a jack post 37. Jack post 37 is provided with the usual or suitable means 38 for fastening it in position between the mine roof and floor. Attached to the sliding journal block 34 is a cable 39, running over pulleys 40, 41 and 42, and having attached thereto a weight 43. The weight 43 thus keeps proper tension at all times upon the cable 17 running over the sheaves 15 and 16.

The embodied form of coal conveying means comprises one or more bottomless scrapers 44, attached to the cable 17 by a relatively short staging or towline 45. In the embodied detailed construction of the scraper 44, it is provided with reinforcing bottom and top flanges 46, and has at the forward top end thereof a reinforcing yoke 47 to permit its passing readily through a pile of coal in its path. The scraper on its

inner side, that is, the side which comes into engagement with the sheave 15 is concaved as shown at 48, so that the scraper will pass readily, neatly and closely about 5 the sheave without slewing or slipping.

The embodied form of means for discharging the coal from the bottomless scraper into the car comprises a sloping platform 50 built at the room neck or mouth and 10 rising outwardly and extending on each side and past or about the sheave 15. In this platform is provided a trap or opening 51 beneath and about which is a chute 52 adapted to direct the coal into the waiting car 5. 15 A guiding strip 53 may be provided on the platform 50 to guide the scraper 44 to the side of the sheave 15 so that it may pass therearound. The platform 50 may be provided with a hinge joint 58, so that it may 20 be raised and thus leave free headroom above the entry track, as shown in dotted lines in Fig. 3.

In Fig. 2 of the drawings a form of the platform and track is shown which leaves 25 the heading track clear of loading or loaded cars where this is desirable. In this form a short spur track 54 is turned into the room neck or mouth of just about sufficient length so that a car turned in thereon will be clear 30 of the heading track. It will be understood that this track need not be extended as the face of the room advances, its purpose being merely to leave the heading track clear. This is desirable where a plurality of 35 motives or teams are employed in drawing out cars along a single heading.

Referring now to the means and method employed in supplying the relatively fixed conveyor with coal as it is dislodged at 40 various points or places across the mine face, and as the mine face recedes or progresses inwardly, due to the dislodgment of the coal, a mining machine 60 is employed, which may be of the general type shown in my copending 45 application for patent, Ser. No. 247,240, excepting that the coal conveying means described therein are omitted, and the coal as it is dislodged by the cutting ring is permitted to fall directly and as it will onto the 50 mine floor. As the machine passes across the room face, the piles of dislodged coal 61 are left behind, and they are obviously out of the operative reach of the fixed path conveyor already described and at different 55 distances therefrom and in different positional relations thereto.

By my present invention, an independently and freely traveling loading machine 62, such as is shown and described in my co-pending application Ser. No. 247,240 which is capable of running over the mine bottom 60 without being in any required or predetermined relation to either the mining machine or the relatively fixed path conveyor, is employed 65 to pick up the dislodged coal 61 from

the mine bottom and to deposit it in position to be taken by the scrapers 44 and to be conveyed thereby over the room floor and to be dumped into the car or cars 5 in the heading. The coal may be conveyed from 70 the piles 61 wherever they may be left by the mining machine and dumped in a pile 63 in the path of the scraper or scrapers 44. It will thus be seen that the independently traveling loader 62 will maintain an operating 75 relation between the mining machine and the relatively fixed path conveyor, without requiring any fixed or predetermined position or relation therebetween. The mining machine is thus unencumbered by any 80 conveyor mechanism of any kind, and the relatively fixed path conveyor need not be kept in any definite or predetermined relation either to the mine face or the mining machine. 85

Means are provided for gripping or pressing the cable to sheave 15, and as embodied, there are provided on the sheave a series of cable gripping members or fingers 64. These fingers are pivotally mounted at 65 upon the sheave 15, and have their tails 66 provided with track rollers 67, which rollers run along an annular track 68 mounted on the pedestal 19. Springs 69 hold the rollers 67 to the track 68 and provide gripping pressure of 90 the fingers upon the cable. The track 68 is shaped so that the fingers 64 firmly grip the cable 17 at the front part of sheave 15 and release the cable as they pass toward the back or inner portion of the sheave. Thus the 100 traveling cable is firmly held to the rotating sheave at all times and slippage is prevented.

The invention in its broader aspect is not limited to the described and illustrated details, but changes may be made therein without departing from the principles of the invention and without sacrificing its chief advantages. 105

What I claim is:—

1. A coal conveying device including in combination a coal delivery device at the mouth of a room, a sheave in fixed position relatively thereto, a sheave near the room face, supporting means therefor removable from one position to another, an endless cable running over said sheaves, and a bottomless scraper connected to and dragged by the endless cable in a unidirectional, endless path. 110

2. A coal conveying device including in combination a pair of sheaves, one located near the room face and one located near the entry, an endless cable passing over the sheaves, a platform with a trap therein near the entry sheave, a chute for directing the coal passing through the trap into a car standing on the entry track, and a bottomless scraper connected to and dragged by said endless cable. 120

3. A coal conveying device including in 130

- combination a sheave at the room neck, a sheave near the room face and a movable mounting therefor including a post carrying the sheave and mounting, means for detachably securing the post between the mine top and bottom, an endless cable running over the sheaves, means for applying tension to the cable and bottomless scrapers drawn by the cable.
- 10 4. A coal conveying device including in combination a sheave at the room neck, a sheave near the room face and a movable mounting therefor including a post carrying the sheave and mounting, means for detachably securing the post between the mine top and bottom, an endless cable running over the sheaves, means for applying tension to the cable, a bottomless scraper attached thereto, whereby it travels unidirectionally in an endless path, a platform at the room neck overhanging a car track and means for discharging the coal from a scraper into a car on the track.
5. A coal conveying device including in combination a platform with a discharge opening therein, a sheave at the platform, an endless cable running over the sheave, a cable guiding and supporting sheave at the opposite end of the path of the cable, a bottomless scraper attached to the cable and passing over said opening to discharge its load and means for driving one of the sheaves.
6. A coal conveying device including in combination a platform with a discharge opening therein, a sheave at the platform, an endless cable running over the sheave, a cable guiding and supporting sheave at the opposite end of the path of the cable, a bottomless scraper attached to the cable and passing over said opening to discharge its load, means for driving one of the sheaves, and gripping devices on said sheave for grasping the cable to drive the cable with the sheave.
7. A coal conveying device including in combination an endless cable arranged in parallel reaches, means for driving and supporting and guiding the cable including a sheave at either end of the path of the cable, a bottomless scraper and a staging line attaching it to the cable and a platform with an opening in the path of the bottomless scraper.
- In testimony whereof, I have signed my name to this specification in the presence of two subscribing witnesses.

KENNETH DAVIS.
